Primary Examiner—James M. Gandy*Assistant Examiner*—Robert M. Spear*Attorney, Agent, or Firm*—Linda M. Buckley[57] **CLAIM**

The ornamental design for a dispensing container cover, as shown and described.

DESCRIPTION

FIG. 1 is a right side elevational view of a dispensing container cover showing my new design;
 FIG. 2 is a rear elevational view thereof, with the cover shown closed;
 FIG. 3 is a front elevational view thereof;
 FIG. 4 is a right side elevational view thereof, the left side elevational view being a mirror image thereof;
 FIG. 5 is a top plan view thereof;
 FIG. 6 is a top plan view, with the cover shown in an alternate open position; and,
 FIG. 7 is a front perspective view of the design of FIG. 4.
